PAUL M. BEARD, OF ST. LOUIS, MISSOURI, ASSIGNEE TO AMERICAN CAR AND FOUNDRY COMPANY, OF ST. LOUIS, MISSOURI, A CORPORATION OF NEW JERSEY.

HOPPER-CAR.

1,109,609.

Specification of Letters Patent.

Patented Sept. 1, 1914.

Application filed April 15, 1912. Serial No. 691,051.

To all whom it may concern:

Be it known that I, PAUL M. BEARD, a citizen of the United States, residing at St. Louis, Missouri, have invented a certain new and useful Improvement in Hopper-Cars, of which the following is a full, clear, and exact description, such as will enable others skilled in the art to which it appertains to make and use the same, reference being had to the accompanying drawings, forming part of this specification, in which—

Figure 1 is a side elevational view of a hopper car of my improved construction with the left hand end thereof shown in vertical section. The sectional portion of this view is taken on a vertical line at the exact longitudinal center line of the car and at the division line between the two parts of the sloping end sheet. Fig. 2 is a plan view of my improved car with parts thereof in horizontal section. Fig. 3 is an end elevation of the car. Fig. 4 is an enlarged vertical section taken approximately on the line 1—4 of Fig. 1. Fig. 5 is an enlarged detail section taken approximately on the line 5—5 of Fig. 4. Fig. 6 is an enlarged detail section taken approximately on the line 6—6 of Fig. 1. Fig. 7 is an enlarged cross sectional view taken approximately on the line 7—7 of Fig. 2.

This invention relates generally to railway cars, and more particularly to a hopper car of the type utilized for the transportation of ore, although cars of practically the same construction can be advantageously utilized in the transportation of coal, coke, gravel and the like.

The principal object of my invention is to provide a hopper car especially adapted for use in the transportation of ore and constructed to meet the requirements and conditions imposed by the ore-carrying service. The conditions at the ore docks are such that restrictions in length, width, car capacity and size of door openings must necessarily be placed upon the various car parts of the equipment used, and the nature of the material to be transported is such that the sides and ends of the hopper cars must be arranged so as to permit a ready discharge and an uninterrupted flow of the lading of the car.

The great desideratum heretofore in hopper car construction within the limitations above mentioned has been; first, to provide

a car of maximum carrying capacity; second, to provide a maximum door opening and third, to arrange a low center of gravity. I accomplish the first and second of these objects by lengthening the hopper, but to maintain the proper slope on the end sheets, it is necessary to reduce the wheel base of the trucks (owing to the restrictions placed upon the length of the car) in order to extend the sloping end sheets of the hopper to a suitable point between the trucks, thereby permitting the door opening to be lengthened proportionately as the length of the hopper was increased. The attainment of the third object is the direct result of the extension of the end hopper sheets to a point as low as conditions permit in order to carry a large percentage of the lading below the supporting members of the car.

In my improved car there is no fixed bottom member, but the doors which are hinged to the lower portions of the side girders form the bottom of the car when said doors are closed, and when the same are open, the entire space between the lower portions of the side girders and the lower ends of the sloping end sheets is free and unobstructed so as to permit the ready discharge of the contents of the car.

In order to close the large opening resulting from the arrangement just described, it is necessary to provide doors and to arrange the same upon the car so that the advantages of the particular hopper construction should be in no wise sacrificed, but, on the other hand, fulfilled in every respect. To attain this object I propose to mount the doors when in normal closed position in a plane substantially above the plane occupied by the lower edges of the sloping end sheets. The open space between the edges of the doors and the edges of the sloping end sheets are closed by suitable load-retaining means extending therebetween, preferably web plates attached to and movable with the doors, but it will be readily understood that any suitable load-retaining means may be utilized and attached to any part of the car provided it closes the opening between the edges of the doors and the sloping end sheets when said doors are closed.

A further object of my invention is to construct a hopper car wherein the principal load-carrying members are in the form of hollow girders arranged at the sides of the

car and extending from bolster to bolster with their ends resting thereupon, thus the hollow side girders combine with the body bolsters to form a rectangular supporting frame for the walls of the car, for the doors that normally close the opening in the bottom of the car and for the load supported by said door and walls.

A further object of my invention is to construct a car with an extra wide dumping opening, which arrangement is particularly desirable inasmuch as a wide opening overcomes any tendency of the load to arch or clog during the dumping or discharging operation.

To the above purposes my invention consists in certain novel features of construction and arrangement of parts hereinafter more fully described and claimed.

Referring by numerals to the accompanying drawings; 1 designates the body bolsters of my improved car, the same being of any suitable construction, and fixed to and extending inwardly from said body bolsters 2, preferably in the form of draft sills 2, preferably in the form of channels.

The side girders, which form the principal load-carrying members of my improved car, are each composed of a base member or bottom chord 4, preferably a channel, a top member or chord 5, preferably a Z-bar, an outer plate 6 and an inner plate or sheet 7. These parts, when properly assembled and united, form a hollow structure of great strength and load-carrying capacity, and the various members or parts forming the girder are continuous from one end of the girder to the other. The upper edge of the outer plate 6 is attached preferably by means of rivets to the depending flange of the Z-bar 5, and the lower edge of said plate 6 is attached preferably by means of rivets to the outer flange of the channel 4. The lower edge of the inner sheet or plate 7 is attached directly to the inner flange of the channel 4 and the upper edge of said sheet 7 is attached directly to the vertically disposed flange on the inner edge of the Z-bar 5. The bottom chord of the side girder or the channel 4 is preferably wider than the Z-bar 5 forming the upper chord, and thus the inner sheet or plate 7 is slightly inclined with its lower edge inside the vertical plane occupied by its upper edge.

Flanged diaphragms 8 are located at suitable distances apart within the hollow girder, said diaphragms being fixed to the sheets 6 and 7 in any suitable manner, preferably by means of rivets. The ends of the girders thus formed rest directly upon and are fixed to the end portions of the bolsters 1, thereby forming a rectangular frame that supports the entire weight of the car body and its load. Positioned on top of the side girders are the upper side

walls 9, the lower edges of which are bent inwardly, as designated by 10, and the extreme lower edges of said walls overlie and are fixed to the upper edges of the plates or sheets 7.

Brackets 11, are fixed to and rest upon the Z-bars 5, and the upper portions of these brackets are fixed to the inwardly bent portions 10 of the side walls, thus forming supports therefor. The side wall 9 is formed of a pair of plates or sheets, and fixed to the edges of the adjacent ends on the outside is a vertically disposed plate 12. Fixed to the corresponding edges on the inner side of these plates is a vertically disposed plate 13 provided with a centrally disposed rib 14, thereby forming a strengthening member or stake for the central portion of the side wall.

The inclined ends of the car are each formed of a pair of slope sheets 15, the same occupying a plane at an angle of approximately 40 degrees relative to a vertical plane. The outer edges of these slope sheets are curved slightly, as designated by 16, and the ends of said curved portions are riveted directly to the corresponding ends of the sheets or plates forming the side walls. The meeting edges of the slope sheets at the center of the car are flanged outwardly, as designated by 17, and united by means of rivets or like fastening devices. The lower portions of the slope sheets extend a substantial distance below the plane occupied by the side girders, as designated by 18 and the extreme lower edges are bent to form a vertically disposed flange 18*. Fixed to the rear side of the flange 18* on the outside thereof is a flanged reinforcing member 19.

By referring to Fig. 1 it will be noted that the lower portions of the slope sheets extend downward over the inner wheels of the trucks as near to the same as is consistent, and by such construction, and the arrangement of the doors hereinafter described, the space within the body of the car is materially increased, thereby increasing the carrying capacity of the car and lowering the center of gravity. Resting upon and fixed to the end portions of the Z-bars 5 are triangular brackets 20, and fixed thereto in any suitable manner, are the ends of transversely disposed, slope sheet supporting members, preferably in the form of channels 21, the same extending entirely across the car body with their top flanges bearing directly against the undersides of the slope sheets 15. The flanges 17 are cut away to accommodate the upper portions of these transverse supporting members. To reinforce and strengthen the construction at points where said flanges are cut away, triangular plates 22 are positioned between the webs of the channels 21 and portions of the flanges 17.

immediately above the cut away portions, said plates being fixed to said parts by rivets or in any suitable manner. The upper edges of the side walls 9 and the upper edges of the slope sheets 15 are surmounted by angles 23 which materially strengthen the upper edges of said walls and end sheets besides forming a finish therefor. The corners between the upper ends of the slope sheets and the side walls are reinforced by gusset plates 24. The opening in the bottom of the car thus constructed is normally closed by a pair of doors 25, the outer edges of which are hinged in any suitable manner to the undersides of the hollow girders. These doors are preferably formed of sheet metal plates, and fixed to the undersides of the ends thereof are vertically disposed webs or flanges 26 which occupy positions immediately adjacent to the flanges 18^a on the lower ends of the slope sheets 15. Fixed to the lower edges of the webs or plates 26 are outwardly projecting plates 27, the outer edges of which are bent upward, as designated by 28, and when the doors are closed these outwardly projecting plates occupy positions immediately beneath the reinforced lower edges 18^a of the slope sheets, as seen in Fig. 5. By this construction, when the car is in use the finer particles of the load sift into the space between the lower edges of the flanges 18^a of the slope sheets and the corresponding portions of the webs or plates 26, thereby forming a packing to prevent the constant loss of the finer particles of the load while the car is in transit. The plates forming the doors 25 are reinforced on their undersides, preferably by means of longitudinally extending members in the form of angles or I-beams.

The doors of my improved car can be equipped with any well known form of operating mechanism, but I prefer to utilize an operating mechanism that includes a winding shaft 29 that is arranged in suitable bearings beneath one of the side girders, a pair of transversely disposed levers 30, winding chains or cables 31 between the shaft 29 and the levers and hooks 32 carried by the ends of the levers 30, which hooks are adapted to engage over the winding shaft to hold the doors in closed position.

By constructing a hopper car as herein shown and described practically the entire weight of the load is carried by the hollow side girders, and by forming said girders comparatively narrow in width and arranging them at the sides of the car, an extremely wide door opening is provided, and for this reason, the load will readily discharge without arching or clogging, which latter effect occurs where a comparatively narrow door opening is formed.

In my improved construction the increased length of the hopper having the required slope of end sheets for the ready discharge of the lading, the extension of the slope sheets downwardly below the plane occupied by the side girders and the proximity of the hopper opening to the track are material factors of bringing about a comparatively low center of gravity of a loaded car, and this feature is especially desirable in cars utilized for transporting heavy loads.

It would be a difficult matter to shape door plates to the contour of the edges of the sloping end sheets, and, at the same time maintain sufficient room under the doors to accommodate the necessary bracing and operating mechanism therefor, and the slope of the door plates in open position would not be sufficient to quickly discharge the lading.

With the door plates shaped as above outlined it would be necessary to raise the hopper opening and decrease the slope of the end sheets in order to increase the slope of the door plates to an inclination corresponding to the required slope of said end sheets. Therefore, to give the proper slope to the doors when in open position, and to maintain the necessary slope in the end sheets, the doors are elevated and hinged in a plane above the lower edges of the sloping end sheets. Such arrangement necessarily causes a space to be formed between the ends of the doors and the lower edges of the sloping end sheets, and this space or gap is closed by means of the plates or webs 26 extending between the ends of the doors and the lower edges of the slope sheets. The side walls 9 merely form retainers for the upper portion of the load, and any portion of the weight of the load which may bear upon said side walls is in turn transmitted to the hollow side girders. The transversely disposed channels 21 form ample supports for that portion of the load above the upper portions of said slope sheets, and it is therefore unnecessary to provide vertically disposed supports between the body bolsters and the upper ends of the slope sheets. The draft sills 2 are connected directly to the bolsters 1, and as the hollow girders rest upon and are directly connected to said bolsters, said girders will bear to a considerable degree, effective in resisting all buffing shocks imparted to the draft sills and bolsters.

In my improved construction of hopper car the slope sheets extend downward over the inner wheels of the trucks, and the lower edges of said slope sheets occupy planes substantially below the plane occupied by the bottoms of the side girders, and the doors closing the opening in the bottom of the hopper are of such length as that they can be readily lowered between the trucks. The doors, when closed, occupy inclined planes

between the under sides of the side girders and the lower edges of the slope sheets and the planes or webs carried by the ends of said doors close the openings between the ends of the bodies of the doors and the edge portions of the slope sheets.

It will be readily understood that minor changes in the size, form and construction of the various parts of my improved car can be made and substituted for those herein shown and described without departing from the spirit of my invention, the scope of which is set forth in the appended claims.

I claim:—

1. A hopper car having sides, sloping end sheets extending below the plane occupied by the sides, the space between the lower portions of said sides and end sheets being open and unobstructed, a door the main body portion of which is arranged in a plane below the sides and above the plane occupied by the lower ends of the sloping end sheets and means carried by said door for closing the space between the ends of said door and the lower portions of the sloping end sheets.

2. A hopper car having sides, sloping end sheets extending below the sides, the space between the lower portions of said sides and end sheets being open and unobstructed, doors for closing the bottom of the car, the main body portions of which doors are arranged below the sides and above the lower portions of the sloping end sheets and means on said door for closing the spaces between the ends of said doors and the lower portions of the sloping end sheets.

3. A hopper car having sides, sloping end sheets extending below the sides, the space between the lower portions of said sides and end sheets being open and unobstructed, doors the main body portions of which are arranged below the sides and above the lower portions of the sloping end sheets and spaced therefrom, and load-retaining means for closing the spaces between the ends of the doors and the sloping end sheets.

4. A hopper car having sides, sloping end sheets extending a substantial distance below the sides, the entire space between the lower portions of said sides and end sheets being open and unobstructed, and load-retaining means closing the openings between the sides and the lower portions of the sloping end sheets.

5. In a hopper car, a pair of sloping end sheets, the lower portions of which extend substantially below the sides of the car and the space between the lower portions of said sloping end sheets and the lower portions of the sides of the car being open and unobstructed.

6. In a hopper car, a pair of sloping end sheets, the lower portions of which extend substantially below the sides of the car, the space between the lower portions of said end

sheets and the sides of the car being open and unobstructed, and load-retaining means for normally closing the opening between the lower portions of said sloping end sheets.

7. In a hopper car, a load-carrying frame comprising a pair of bolsters, a pair of side girders, and sloping end sheets supported from the bolsters, the lower ends of which end sheets extend a substantial distance below the side girders and the space between the lower portions of the sloping end sheets and side girders being open and unobstructed.

8. In a hopper car, the combination with a supporting frame comprising a pair of bolsters, a pair of side girders, of sloping end sheets positioned above the bolsters and extending a substantial distance below the side girders the space between the lower portions of said end sheets and side girders being open and unobstructed, and load-retaining means between the lower portions of said sloping end sheets.

9. In a hopper car, the combination with a supporting frame comprising a pair of bolsters, a pair of side girders of sloping end sheets positioned above the bolsters and extending below the side girders, the space between the lower portions of said end sheets and side girders being open and unobstructed, load-retaining means between the lower portions of said sloping end sheets, and walls supported by the side girders.

10. In a hopper car, a rectangular frame, sloping end sheets arranged at the ends of said frame, the lower portions of which sheets extend substantially below the plane occupied by the bottom of said frame, the space between the lower portions of said end sheets and the side members of the frame being open and unobstructed, and load-retaining means for normally closing the opening between the sides of the frame and the downwardly extending portions of the end sheets.

11. In a hopper car of the class described, the combination with a supporting frame comprising a pair of body bolsters and a pair of hollow side girders, of sloping end sheets supported by said body bolsters, the lower portions of which end sheets project a substantial distance below the hollow side girders, and drop doors hinged to the side girders and adapted to form the bottom of the car.

12. In a hopper car, the combination with a supporting frame comprising a pair of bolsters, hollow side girders, the ends of which rest upon the end portions of said bolsters, of sloping end sheets supported by said bolsters, the lower portions of which end sheets extend a substantial distance below the hollow side girders, and drop doors hinged to said side girders and adapted to form the bottom of the car.

13. In a hopper car, the combination with a supporting frame comprising transversely disposed end members and a pair of hollow side girders, of sloping end sheets arranged between the end portions of said hollow side girders, the lower portions of which end sheets extend below the side girders, and drop doors hinged to said side girders and adapted to form the bottom of the car.
14. In a hopper car, the combination with hollow side girders each comprising a bottom chord, a top chord, and web plates connecting said chords of sloping end sheets arranged between the end portions of said hollow side girders.
15. In a hopper car, the combination with hollow side girders each comprising a bottom chord, a top chord, web plates connecting said chords, and diaphragms arranged on the interior of said hollow girders of drop doors hinged to the lower portions of said girders and adapted to form the bottom of the car.
16. In a hopper car, a pair of hollow side girders, side walls positioned on said side girders, slope sheets forming inclined ends for the car body and drop doors hinged to the lower portions of the hollow side girders, which doors when closed form the bottom of the car.
17. In a hopper car, a pair of hollow side girders, side walls positioned on said side girders, slope sheets forming inclined ends for the car body, the lower ends of which slope sheets extend below the side girders and drop doors hinged to the lower portions of the hollow side girders, which doors when closed form the bottom of the car.
18. In a hopper car, a pair of hollow side girders, side walls supported by side girders, slope sheets forming inclined ends for the car body the lower portions of which extend a substantial distance below the side girders, transversely disposed supporting members positioned beneath the slope sheets, the ends of which supporting members rest upon the end portions of the side girders, and drop doors hinged to the lower portions of the hollow side girders, which doors when closed form the bottom of the car.
19. In a hopper car, a pair of side girders, side walls positioned on said side girders, slope sheets forming inclined end walls for the car body, the lower portions of which slope sheets extend below the side girders, doors hinged to the side girders for closing the opening in the bottom of the car, and web plates on the ends of said doors, which web plates occupy positions immediately adjacent to the lower edges of the inclined end walls of the car body.
20. In a hopper car, a pair of side girders, side walls supported by said girders, slope sheets forming inclined end walls for the car body, the lower portions of which end walls extend below the side girders, doors hinged to the side girders and normally closing the opening in the bottom of the car, web plates on the ends of said doors, which web plates occupy positions immediately adjacent to the lower edges of the inclined end walls and outwardly projecting plates on the lower edges of the web plates, which outwardly projecting plates extend beneath the lower edges of the inclined end walls.
21. In a hopper car, a pair of bolsters, a pair of side girders, the ends of which rest upon the end portions of the bolsters, side walls positioned on the side girders, transversely disposed supporting members on the ends of the side girders, slope sheets forming inclined ends for the car body, which slope sheets rest upon the transversely disposed supporting members, and a pair of drop doors hinged to the lower portions of the hollow side girders, which doors when closed form the bottom of the car.
22. In a hopper car, a pair of side girders, side walls positioned thereon, transversely disposed supporting members on the ends of the side girders, inclined end walls supported by the transversely disposed members, the space between the side girders and lower portions of the inclined end walls being open and unobstructed, doors hinged to the side girders which doors when closed form the bottom of the car, and means on said doors for closing the spaces between the ends of said doors and the lower portions of the inclined end walls.
23. In a dumping car, the combination with load carrying members forming side girders each comprising a base member, a top member and transversely spaced apart plates disposed between said base and top members of drop doors hinged to the lower portions of said side girders and adapted to combine in closing the space between said side girders and forming a bottom for the car.
24. In a dumping car, the combination with load carrying members forming side girders each comprising a bottom channel, a Z bar and spaced apart plates connecting said channel and Z bar of drop doors hinged to the lower portions of said side girders and adapted to combine in closing the space between said side girders and forming a bottom for the car.
25. In a dumping car the combination with hollow side girders forming load carrying members, of sloping end sheets, the lower portions of which extend a substantial distance below the side girders, and load retaining walls supported by said girders.
26. In a dumping car, hollow side girders forming load carrying members load retaining walls supported from said girders and sloping end sheets arranged between the end portions of the side girders and retaining

- walls, which sloping end sheets form load carrying members and are supported from said girders. 27. In a dumping car, hollow side girders forming load carrying members slope sheets supported from said girders, the lower portions of which said slope sheets extend below said girders, and door suspending means supported from said girders. 28. In a dumping car, hollow side girders having a relatively broad base the space between said girders being open and unobstructed, sloping end sheets, the lower portions of which extend substantially below the hollow side girders, and discharge opening doors suspended from said broad base, which doors combine to close the space between the girders and form a bottom for the car. 29. A dumping car having side walls, said walls comprising double plate girders load retaining walls bracketed to the top of said girders and drop doors hinged to the lower portions of said girders and combining to close the space between said girders and when closed to form a bottom for the car. 30. A dumping car having a side wall, the lower portion of said wall comprising transversely spaced apart plates a top chord member and a bottom chord member connecting said plates and the upper portion of said wall consisting of a single thickness of plate. 31. A dumping car having a hollow side wall of increasing thickness toward the bottom thereof and comprising a pair of spaced plates, a top chord connecting the upper portions of said plates and a bottom chord connecting the lower portions of said plates. 32. A dumping car having a hollow side wall of increasing thickness toward the bottom thereof and comprising a pair of spaced plates, a top chord and a bottom chord, and means attached to the bottom chord of said wall adapted to support discharge opening doors. 33. In a dumping car, the combination of a double plate girder, a bottom chord forming part of said girder and door supporting means carried by said chord. 34. In testimony whereof I hereunto affix my signature in the presence of two witnesses, this eleventh day of April, 1912.

PAUL M. BEARD.
